[57] CLAIM

The ornamental design for a wet wipe dispensing port for pop-up dispenser, as shown and described.

DESCRIPTION

FIG. 1 is a perspective view of the wet wipe dispensing port showing our new design;

FIG. 2 is a top plan view thereof;

FIG. 3 is a bottom plan view thereof;

FIG. 4 is a sectional view thereof taken along line 4—4 of FIG. 2.

The broken line showing a pop-up dispenser is for illustrative purposes only and forms no part of the claimed design.

FIG. 1

FIG. 2

FIG. 3

FIG. 4
